UNITED STATES PATENT OFFICE

GUSTAV EGLOFF AND HARRY P. BENNER, OF CHICAGO, ILLINOIS, ASSIGNORS TO
UNIVERSAL OIL PRODUCTS COMPANY, OF CHICAGO, ILLINOIS, A CORPORATION OF
SOUTH DAKOTA

PROCESS FOR CRACKING HYDROCARBON PRODUCTS

No Drawing. Application filed April 25, 1921, Serial No. 464,367. Renewed July 2, 1928.

This invention relates to cracked hydrocarbon products and process of producing same and relates more particularly to the cracking of a wax oil.

5 The object of the invention is to crack wax oil as, for example, wax oil obtained from the distillation of Mexican crude petroleum so as to convert substantial percentages thereof into light hydrocarbons as, for example, gasoline or gasoline-like bodies.

The invention will be more clearly understood from the description of the process as carried out by us and hereinafter fully set forth.

15 For example, a wax oil, resulting from the atmospheric distillation of a Mexican crude oil of substantially 20° Baumé gravity, in accordance with our process, is subjected to pressure distillation under an initial pressure of 350 pounds per square inch and a liquid temperature of 820° F., which pressure is gradually reduced down to 80 pounds per square inch and which temperature is increased to a liquid temperature of 887° F.

25 By carrying out the process under such conditions of temperature and pressure, a pressure distillate equal to 60 per cent of the oil charge may be recovered, having an average Baumé gravity of 50°. The pressure distillate, upon 30 redistillation, produces 75 per cent gasoline, having an initial end point of 103° F., an end point of 428° F., a Baumé gravity of 57.7° and an unsaturated hydrocarbon content of 15 per cent. Calculated upon the basis of the

35 Mexican wax oil cracked, 45 per cent of the charge may be converted into marketable gasoline. During the operation of the process, 35 per cent of the still charge may be recovered as pressure distillate per hour.

40 More specifically, the Mexican wax oil treated had a Baumé gravity of 19.6° and initial boiling point of 298° F., while 95 per cent of the oil boiled below 785° F. and contained 64 per cent unsaturates. This oil, 45 when treated in accordance with our process, can be made to yield 60 per cent pressure distillate, 33.5 per cent residuum, with a carbon and gas production of only 6.5 per cent of the oil charge.

50 As above pointed out, the pressure on the oil

is gradually reduced from 350 to 80 pounds per square inch, while the temperature is slightly increased, the furnace temperature during the operation of the process ranging from a minimum of 1160° F. to a maximum of 1450° F., while the liquid temperature of the oil ranges from 820° F. to 887° F. and the vapor temperature from a minimum of 783° F. to a maximum of 890° F.

When subjected to redistillation, 80 per cent of the gasoline produced boils below 350° F. and the same has a light, straw color. The residuum, upon retreatment, yields 27.9 per cent coke, while 70 per cent of the residuum boils below 820° F.

From the foregoing, it will be seen that our process permits of the recovery of a very substantial yield of gasoline from a wax oil by subjecting the same to pressure distillation under a gradually decreasing pressure.

We claim as our invention:—

A process for cracking wax oil, consisting in introducing a body of oil to a still, in maintaining said oil while undergoing distillation in the still under a gradually decreasing self imposed vapor pressure ranging from a maximum of at least 350 pounds per square inch, and in increasing the temperature substantially as the pressure on the oil is decreased.
